(57) **CLAIM**

The ornamental design for a display screen or portion thereof with an icon as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a portion of a display screen showing our new design for a display screen or portion thereof with an icon; and,

FIG. 2 is a front view of a second embodiment thereof. The dot-dashed-lines illustrate the perimeters of portions of a display screen and form no part of the claimed design.
